US00D910469S

(12) **United States Design Patent** (10) Patent No.: **US D910,469 S**
(45) Date of Patent: **** Feb. 16, 2021**

(54) **RANGEFINDER**

(71) Applicant: **JENOPTIK Advanced Systems GmbH**, Wedel (DE)

(72) Inventor: **Uwe Schaller**, Kahla (DE)

(73) Assignee: **Jenoptik Advanced Systems GmbH**, Wedel (DE)

(**) Term: **15 Years**

(21) Appl. No.: **35/508,118**

(22) Filed: **Mar. 15, 2019**

(80) **Hague Agreement Data**

Int. Filing Date: **Mar. 15, 2019**

Int. Reg. No.: **DM/204652**

Int. Reg. Date: **Mar. 15, 2019**

Int. Reg. Pub. Date: **Dec. 13, 2019**

(30) **Foreign Application Priority Data**

Sep. 18, 2018 (DE) 40 2018 100 937.7

(51) LOC (13) Cl. **10-04**

(52) U.S. Cl.

USPC **D10/70**

(58) **Field of Classification Search**

USPC D10/104.1, 70, 65–66, 101, 75; D16/202

CPC G01S 17/931

See application file for complete search history.
